UNITED STATES PATENT OFFICE.

IGNAZIO PIERMATTEI, OF LANDISVILLE, NEW JERSEY.

PAPER-RECEPACLE-MAKING MACHINE.

Application filed October 20, 1926. Serial No. 142,893.

The invention relates to machines for making paper receptacles and particularly for paper receptacles used in connection with toy torpedoes, in which an explosive charge 5 is placed with gravel.

A further object is to provide a paper receptacle making machine wherein a strip of paper is fed into the machine by feeding mechanism, twisted around spindles having 10 a planetary movement, and which spindles, during their planetary movement, move adjacent mechanism which cooperates with the portion of the container extending beyond the spindles and folds and twists said portion 15 of the container for closing one end thereof. Also to provide in connection with the feeding mechanism, severing means which will sever the strip of paper.

A further object is to provide paper strip 20 feeding mechanism, which will feed simultaneously to the spindles a narrower strip of paper which will be twisted around the spindles simultaneously with the wide strip in a position where it will be spaced from the 25 sides of the wide strip, thereby forming a shell over the opposite edges of which the ends of the container may be folded inwardly for forming a substantially cylindrically shaped receptacle. Also to provide means 30 whereby the length of the strips, both narrow and wide, fed to the spindles may be varied.

A further object is to provide a large stationary gear, with which the spindle rotating pinions mesh during the rotation of a disc to which the spindle frames are pivotally connected, and to proportion said gears whereby when the spindles are adjacent the discharge end of the feeding mechanism, 45 spring closed gripping jaws carried by the spindles will be in position for gripping the ends of the paper strips. Also to provide means cooperating with the spindle gripping jaws whereby when they assume positions adjacent the strip feeding mechanism, said gripping jaws will be automatically opened, and allowed to close upon the further movement of the spindles.

A further object is to provide yieldable 50 means with which the spindles engage in their planetary movement for holding the strips of paper as they are wrapped around

the spindles. Also to provide an arcuately shaped tapered slot through which the portions of the containers extending beyond the 55 ends of the spindles pass and are twisted to closed position.

A further object is to provide a finger extending into the restricted end closing slot for engaging the portion of the container 60 beyond the spindles for folding one side thereof inwardly adjacent the seam or end of the outer strip, thereby locking the end of the strip by the following twisting operation, and means for moving said finger outwardly thereby preventing tearing of the 65 projecting portion of the container during its further movement.

A further object is to provide the spindle carrying frames with arms having rollers 70 disposed in a cam slot in a stationary disc, and said cam slot with a U-shaped portion adjacent the feeding mechanism, and into which the roller passes thereby pivotally moving the spindle and its frame to speed the same up in its movement with its gear in mesh with an inwardly movable segment of the large gear, thereby allowing the spindle to have a slight pause at the point of gripping for taking care of the time incident 75 to the gripping operation and feeding of the strips under the gripping jaw of each spindle.

A further object is to provide a pivotally mounted member having a yieldable projection and positioned whereby as the spindles pass from the twisting slot, pressure will be applied on the twisted ends of the container, thereby insuring a positive closing of the 80 end of the receptacle.

A further object is to provide a cam slot 85 into which rollers carried by the spindle frames pass, and which rollers force forwardly the spindles thereby pulling the gripping jaws from the formed containers, and 90 rods slidably mounted in said spindles and having lugs extending beyond the sides thereof, and which rods engage cam means for holding said rods against rearward movement as the spindles are retracted by the 95 engagement of the rollers in the cam slots, thereby causing said rods to force the formed containers from the spindles, into a hopper 100 and before they again reach the feeding

mechanism, and spring means for returning said rods to normal inner position after their rear ends have passed out of engagement with the cam which cooperates with their 5 rear ends.

A further object is to provide means whereby the narrow and wide strips of paper may be discharged in engagement with each other to the spindles, and frictional gripping means for holding said strips of paper in proper position in relation to each other after the severing operation and during the winding of the same on the spindles.

A further object is to provide means 15 whereby all of the mechanism may be operated from a single source of power where power driven, and manual means for operating the device if desired.

With the above and other objects in view 20 the invention resides in the combination and arrangement of parts as hereinafter set forth, shown in the drawings, described and claimed, it being understood that changes in the precise embodiment of the invention may 25 be made within the scope of what is claimed without departing from the spirit of the invention.

In the drawings:

Figure 1 is a view in elevation of the 30 machine.

Figure 2 is a top plan view of the machine.

Figure 3 is a transverse sectional view taken on line 3—3 of Figure 2.

Figure 4 is a vertical longitudinal sectional view taken on line 4—4 of Figure 2.

Figure 5 is a view in elevation of the feeding mechanism looking in the direction of the arrow *a*, Figure 2.

Figure 6 is a horizontal sectional view through one of the spindles and its frame.

Figure 7 is a view in elevation of a portion of the large gear rotatable member and cam slot, showing the gear segment forced inwardly for allowing advance of the spindles.

Figure 8 is a top plan view of the spindle advancing cam.

Figure 9 is a perspective view of said cam, 50 shown in Figure 8.

Figure 10 is a perspective view of the container presser, and a portion of one of the spindles.

Figure 11 is a longitudinal sectional view 55 through the container presser.

Figure 12 is a perspective view of the cutter for the wide strips of papers.

Figure 13 is the cutter for the narrow strips of papers.

Figure 14 is a perspective view of one of the spindles in closed position, and a portion of the opening arm.

Figure 15 is a view similar to Figure 14 showing the spindle jaw in open position to grip the strips.

Figure 16 is a perspective view of the strip discharging chute.

Figure 17 is a vertical longitudinal sectional view of the discharge end of the strip discharging chute.

Figure 18 is a perspective view of the wide and narrow strips showing the same in their relative positions.

Figure 19 is a perspective view of the strips after they have been twisted around 75 one of the spindles.

Figure 20 is a perspective view of one of the containers after one side thereof has been forced in adjacent the outer end of the wide strip.

Figure 21 is a perspective view of the end of the container after the twisting operation.

Figure 22 is a side elevation of a modified form of spindle wherein a paper guide column is mounted on the spindle.

Figure 23 is a front elevation of the spindle shown in Figure 22.

Referring to the drawings, the numeral 1 designates the bed plate of the machine, which is preferably supported on legs 2. Extending upwardly from opposite sides of the bed plate 1 are brackets 3, in bearings of which the transversely disposed shaft 4 is rotatably mounted. The shaft 4 at its outer end is provided with a worm gear 5, with which the worm 6 meshes, and which worm 6 is carried by a shaft 7, one end of which is provided with a hand wheel 8 adapted to be grasped by the operator for manual operation if desired, for instance for rotating the parts during repair or adjustment. Secured to the shaft 7 is drive pulley 9, over which a belt 10 extends, and which belt extends downwardly over the pulley 11 carried by the motor 12, which motor is preferably disposed beneath the bed plate 1. Surrounding the shaft 4 is a stationary sleeve 13, in which said shaft rotates, and which sleeve 13 at its outer end is provided with a flange 14 which is anchored by means of bolts 15 to one of the brackets 3. The inner end of the sleeve 13 is secured by means of bolts 16 to a cam disc 17 having a cam slot 18 therein, and which cam disc remains stationary during the operation of the machine, and secured to the cam disc 17 by means of bolts 19 is a large gear 20, which large gear remains stationary at all times. Disposed adjacent the cam disc 17 and secured to the shaft 4 and rotatable therewith is a spindle carrying disc 21, to which are pivotally connected at 22 the spaced arms 23 of the spindle frame 24, in which are rotatably mounted sleeves 25 having pinions 26, and which pinions mesh with the large gear 20. It will be seen that as the spindle carrying disc 21 is rotated in the direction of the arrow *a*, Figure 1, with the pinions 26 in mesh with the large stationary gear 20, said pinions 26 will have a planetary action, and the sleeves 25

will be rotated, and as said sleeves are slidably keyed at 27 to the spindle shafts 28, the spindles 29 will be simultaneously rotated for twisting the main and auxiliary 5 tapered strips 30 and 30^a around the spindles. One of the arms 23 of each spindle frame 24 is provided with angularly disposed arms 31 having rollers 32 thereon, and which rollers are disposed in the cam slots 10 of the cam disc 17 and maintain the spindle frames 24 radially disposed during the greater portion of their movement. The paper strips 30 and 30^a are fed to the spindles by feeding mechanism hereinafter set 15 forth through the discharge end 33 of the paper feed chutes 34 and 35 which merge together, and as the spindles approach a horizontal position as shown in Figure 4, and at which time the gripping jaws 36 of 20 the spindles are automatically opened for receiving the ends of the paper strips and gripping and frictionally holding the same. It is obvious that a slight delayed action is necessary for accomplishing the gripping 25 operation, and to obtain this result the spindle frames, as the spindles approach the gripping position, are allowed to advance rapidly in relation to the speed of rotation of the disc 21, and to be then forced to radial position, which will give a slight delayed operation of the spindle frame for the gripping operation. To accomplish the above result, and referring particularly to 30 Figure 7, a segment 37 of the large stationary gear 20 is pivotally mounted at 38, and the cam slot 18 is provided with an inwardly extending V-shaped portion 19, into which the rollers 32 carried by the arms 31 pass, as the frames approach the gripping 35 position, therefore it will be seen that the V-shaped portion of the cam slot 18 will tilt the arms 31 of the spindle frames inwardly, thereby allowing the spindles 29 to advance in relation to the speed of rotation of the disc 21 as clearly shown in Figure 7. Referring to Figure 7, it will be seen that the gear segment 37 has been moved inwardly against the action of the spring 40 for allowing the tilting operation of the 45 frame, as the roller 32 passes through the portion 19^a of the cam slot 18 it will be seen that the spindle frame 24 will be allowed to have a retarded action in moving to a radial position, and which action will be sufficiently retarded to allow for the gripping 50 operation. The strips are cut from rolls as they are fed through the mechanism hereinafter set forth.

As the strips are cut from the paper fed 55 into the machine, they are twisted around the spindles 29 with the narrow strip 30^a inside thereof to form a reinforcing for the containers as clearly shown in Figure 19, and after which the ends are folded over the ends 60 of the reinforcing. As the strips are twisted around spindles during their planetary action and moving in the direction of the arrow *a*, Figure 1, they are engaged by the spring arms 40 carried by the supporting bracket or arcuate plate 41, which is supported by the bracket arm 42. The spring arms 40 press on the strips wrapped around the spindles and prevent unwinding thereof. It will be noted by referring to Figure 15 65 that the strip 30^a is narrower than the strip 30, and that one side of the strip 30 extends beyond the outer end of the spindle 29, therefore it will be seen that the portion 30^b of the container, which extends beyond the outer end of the spindle 29 is to be folded 70 inwardly for closing one end of the container as shown in Figure 21. However to get the best results and a locked seam a finger 43 is provided, which finger is carried by a transversely movable rod 44, which is normally forced in one direction by means of a coiled spring 45, and which finger is adapted to be moved inwardly into the cam slot 46 immediately before the container end enters 75 said slot for crimping the end 30^b inwardly at 30°, Figure 20, adjacent the end fold 30^b of the outer strip of paper 30, and then to immediately move outwardly so it will not tear the adjacent portion 30^c of the container end, and which portion 30^c moves 80 through the restricted slot 46 whereby it gets a twisting action which folds in the end of the container. To move the rod 44 longitudinally said rod is provided with a cam plate 47 which is in the path of the rollers 48 carried by the spindle frames 24, and it will be seen that as said rollers engage the cam plate 47, the rod 44 will be immediately moved in one direction, which will force the finger 43 into the cam slot 46, and as said rollers pass 85 out of engagement with the plate 47, spring 45 will move the rod 44 in the opposite direction, thereby withdrawing the finger 43 from the cam slot 46. The cam slot member 49 is supported by brackets 50, which are secured to one of the brackets 3. As the spindles continue in their rotation in the direction of the arrow *a*, Figure 1, with their portions 30^c in the cam slot 46 which is restricted to a vanishing portion, said portions 90 95 will be twisted for closing the end of the container, however to more positively apply pressure to the ends of the container a pivoted presser member 51 is provided on the bed plate 1, and which is pivotally connected at 52 to a bracket 53, and which member is normally forced to an upwardly and inclined position by means of a spring 54 to a position where the stop 55 carried thereby will be in the path of the ends of the spindles so that said spindles will force the 100 105 110 115 120 125 130 135 140 145 150 155 160 165 170 175 180 185 190 195 200 205 210 215 220 225 230 235 240 245 250 apply pressure to the closed ends of the receptacle. Plunger 56 is preferably bevelled at 57 to allow the spindles to easily cam past the same into engagement with the member 55 and to slide off said spring actuated plunger during the continuous rotation of the spindle in its planetary movement.

The rollers 48 engage the rear side of the guide ring 58 during the operation of the device as clearly shown in Figure 2, however, it is obvious that when the spindles have passed through the operations for closing the end of the receptacle it will be necessary to remove said receptacles from the spindles, and this removing operation can be easily facilitated by loosening the receptacles on the spindles, and to accomplish the above result the next operation is broadly to force the spindles 19 outwardly without 20 outward movement of the gripping jaws 36, thereby releasing the binding action of the jaws 36 within the container, and then to force the loosened container from the spindle. The gripping jaws 36 have sufficient tension to hold the ends of the strips during the twisting operation, but not sufficient tension or frictional holding power to prevent the formed receptacles to be forced outwardly from the spindles. To accomplish the above 30 result the rollers 48 pass through the cam slot 59 at the lower side of the ring 58, and as said rollers are carried by bars 60 slidably mounted in the spindle frames 24, and which bars are connected by yokes 61 to the spindle shank 28, said spindle shanks and the spindles 29 will be moved in the direction of the arrow *b*, Figure 6, as they are slidably keyed at 27. At the same time the container removing rod 62 moves forwardly with the spindles 29, however the gripping jaw 36, which is carried by the sleeve 25 remains stationary with the exception that it rotates, therefore it will be seen that the gripping jaw 36 will be pulled 40 from the container during the outer axial movement of the container, as the rollers 48 pass through the cam slot 59, the spindle 29 will be pulled inwardly, however the container removing rod 62 will be held against inward movement by the engagement of the rear end thereof with the arcuate plate 63, consequently its lugs 64, which extend outwardly from the opposite side of the spindle slot 65 will engage the inner end of the receptacle and will force the receptacle from the spindle, thereby allowing the receptacle to drop into the hopper 66 and to be discharged therefrom into a suitable receptacle 55 67. The gripping jaws 36 have only sufficient gripping action to hold the containers against outward axial movement under normal conditions, but not sufficient gripping action to prevent the outward removal of the receptacle upon outward movement of the spindles 29, during the jaw removing

operation. After the inner end of the rods 62 pass out of engagement with the arcuate plate 63, the coiled springs 68 which surround said rods and are interposed between the washers 69 and the spindle shanks 28, force said rods 62 inwardly to their normal positions and the spindles are again in position to grip strips at the point of feeding. Gripping jaws 36 are pivotally mounted at 70 on sleeves 71, which are clamped on the sleeves 25 and are normally held in closed positions by means of coiled springs 72.

Referring to Figures 4 and 5 wherein the feeding mechanism is particularly shown, said feeding mechanism is supported by a bracket 73 and the strips 30 and 30^a are fed towards the spindles 29 when in gripped position through the guide chutes 34 and 35. The wide strip 30 through the chute 34 and the narrow strip 30^a through the strip 35. The strips merge together at the discharge end 33 of the chutes and pass under a presser plate 74 which presser plate is forced downwardly by the pivoted right angularly shaped member 75 which is carried by the pivoted arm 76, and which arm 76 is normally forced rearwardly by means of the coiled spring 77 connected thereto and anchored at 78 to the fixed arm 79. Arm 76 is provided with a right angularly disposed arm 80 disposed in the path of the pivoted trip lever 81, which is pivotally connected at 82 to the bracket 83 and has its angularly disposed arm 84 pivoted whereby when said trip lever 81 is forced towards the spindles 29 by the engagement of the member 85 carried by said lever with the rotatable cam 86, which rotates in the direction of the arrow *b*, Figure 5, the arm 84 will be in the path of the gripping jaw arm 87 of the adjacent spindle, thereby raising the gripping jaw at the time of feeding of the ends of the strips 30 and 38 to the spindle. The continued rotation of the cam 86 is timed whereby the gripping jaw is released and the retarded operation of the spindle frames above referred to is to allow the positive gripping. As the arm 81 moves forwardly it engages the arm 80 and raises the gripping member 75, thereby allowing the strips 30 and 30^a to be twisted around the spindle. However to positively feed the strips 30 and 30^a a plurality of feed rollers 87 and 88 are provided, which rollers extend into opposite sides of the chutes 34 and 35 and grip the strips of paper, that is when the feed rollers 87 are rotated to positions where their corners 89 will engage the strips of paper and force them against the rollers 88, which are preferably rubber friction rollers, therefore it will be seen that the strips of paper are positively gripped and fed to the spindles when said spindles reach and pass the gripping position. It is obvious that the length of the paper strip fed to the device may be varied.

by varying the position of the rollers 87 and 88 on their drive shafts 90 for varying the position of the shoulders 89 of the gripping rollers. The mechanism shown in Figure 5 is in the cutting position, that is, the pivoted cutters 91 and 92 are in closed position and have severed the strips 30 and 30^a, and it will be noted that the severed portion of the strip 30^a is shorter than the severed portion of the strip 30, which will leave the extension of the strip 30 extending beyond one end of the strip 30^a, and which extension, after the container is formed on the spindle will make a turn around the container for entirely concealing the reinforcing strip therein. The friction rollers 88 are carried by shafts 93 which extend through bearings of the brackets 73 and the shafts 90 also extend through bearings of said brackets 78 and have their outer ends geared together by a gear train driven by one of the shafts 90, and which shaft is provided with a gear 94 which is rotated by a worm 95, said last named shaft 90 has mounted thereon a gear 96 which meshes with a gear 97, and which gear meshes with a gear 98 which in turn drives the gear 99, which meshes with the gear 100. Gear 98 also drives the gear 101, and the gear 97 drives the pinion 102, and the gear 103 through the intermediate gear 104. The gear 97 is relatively wide and also drives the idle gear 105, which in turn drives the gear 106 which meshes with the small gear 107, therefore it will be seen that all of the feed and friction rollers of the feeding mechanism will be simultaneously rotated in the direction of the various arrows shown in Fig. 5. The worm 95 is carried by a shaft 108, which shaft is provided with a slidable clutch member 109 which cooperates with a conventional form of cone clutch 110 carried by the pulley 9 and shaft 7, and the coiled spring 111 normally maintains said clutch elements in clutched relation whereby during the operation of the motor 12 the spindle and feeding mechanism are simultaneously operated. The clutch element 109 has connected thereto a lever 112 which lever when moved in the direction of the arrow c, Figure 1, will stop the feeding mechanism and a spring arm 113 is preferably provided for cooperating with one side of the lever 112 and holding the same in open position.

The pivoted cutter blades 91 and 92, which are shown in Figure 5 in closed position where they have severed the strips 30 and 30^a for allowing the severed ends of the strips to be pulled onto the spindle are operated from adjacent shafts 90, and which shafts are provided with cams 114 and 115 which rotate in the direction of rotation of the feed rollers 87 carried by the shafts 90, and in their rotation engage the cam noses 116 of the arms 117 and 118 of the bell crank levers 119 and 120, arms of which

overlie the outer ends of the pivoted cutter blades 91 and 92 and force the same to closed position thereby severing the strips 30 and 30^a transversely and in proper lengths for forming the receptacles. As soon as the cam members 114 and 115 pass the cam noses 116 which will release pressure on the cutter blades 91 and 92, the springs 121 and 122 will immediately move said cutter blades to open positions. After the cutting operation the cam 86 will force the lever 87 towards the spindle 29 for opening said spindle and will simultaneously raise the presser member 75 thereby releasing the severed ends of the strips and allowing the same to be pulled from the chutes by the rotation of the spindles. At the same time additional paper is fed inwardly by the other rollers 87 and 88. To prevent the strips 30 and 30^a from coming out of the chutes after a severing operation plates 123 are provided which rest upon the strips and exert sufficient frictional power thereon to prevent rearward slipping of the paper. The strips of paper 30 are preferably carried in rolls 124, which are mounted on a roll rack 125, however it is to be understood that this mechanism may be varied as desired.

From the above it will be seen that a container making machine is provided wherein strips of paper are fed into the machine by a feeding mechanism, wrapped around spindles as they reach the feeding position, conveyed from the feeding position by the spindles, crimped inwardly on one side adjacent the end of the last wrapping, thereby forming a locked joint, the projecting ends so crimped twisted, additional pressure applied on the twisted end of the receptacle, the gripping jaws withdrawn from the receptacle and means provided for forcing the receptacle so formed from the spindle. It will also be seen that the containers can be used for various purposes, however they are particularly adapted for use in making toy torpedoes, and it will be noted the machine closes one end only of the container, and where used in connection with torpedoes, the explosive charge and gravel are placed in the open end of the receptacle and the portion extending beyond the reinforcing machine is folded inwardly for closing the torpedo, said last named folding is usually a manual one.

The knife 91 is maintained normally open by means of the spring 126 and the lever 81 in inoperative position by the coiled spring 127.

Referring to Figures 21 and 22 wherein a modified form of spindle is shown, the spindle is provided with a paper guide 128 which is in disc form and held on the spindle by means of a set screw 129. It will be noted that the disc is provided with a

recess 130 extending inwardly from one side thereof, which disc will allow free movement of the gripping jaw 36 in its movement to open or closed position, and such a 5 guide may be used if desired.

The invention having been set forth what is claimed as new and useful is:—

1. A machine for making paper receptacles, said machine comprising a paper strip feeding mechanism, said feeding mechanism having means for feeding a wide strip of paper and a narrow strip of paper with the sides of the narrow strip spaced inwardly from the sides of the wide strip, 10 a rotatable spindle, means for gripping and holding the ends of both strips as they are twisted around the spindle and means for folding the portion of the wide strip extending beyond the end of the spindle.

20 2. A machine for making paper receptacles and comprising a paper strip feeding mechanism, a plurality of rotatable spindles having a planetary movement, gripping members carried by said spindles and adapted to grip the strip as fed thereto, means for holding the strips against unwinding on the spindles during the planetary movement thereof, means for folding in the outer ends of the strips onto the ends 25 of the spindles, means for withdrawing the gripping jaws in an axial direction from the receptacles, thereby loosening the receptacles on the spindles and means for forcing the receptacles from the spindles before the spindles reach the strip gripping position.

3. The combination with a paper making receptacle machine, said machine comprising a paper strip feeding mechanism, a plurality of spindles having a planetary movement, said spindles being pivotally connected to a rotatable member, cam slot controlled means for preventing pivotal movement of the spindles on the rotatable member and cam slot controlled means for allowing an advance and retarded movement of the spindles at the feeding point whereby a delayed action is obtained as the strips are fed to the spindles.

4. The combination with a paper receptacle making machine, said machine comprising paper strip feeding mechanism, a plurality of spindles having a planetary movement and around which the paper strips are wrapped, gripping jaws carried 55 by said spindles and normally maintained closed, means for opening said gripping jaws at the point of paper strip feed and closing said jaws, of means whereby said spindles as they approach the strip feeding 60 point are allowed to have an advance movement in relation to the other spindles and a retarded movement at the point of feed, thereby allowing a slight slowing up or pause for the gripping operation.

65 5. The combination with a paper recep-

tacle making machine having a paper strip feeding mechanism; of a plurality of spindles around which the paper strips are twisted, means for preventing untwisting of said strips, gripping jaws carried by said spindles, means for opening and closing said gripping jaws adjacent the point of feed, said spindles having shafts, pinions carried by said sleeves, a large stationary gear with which said pinions mesh, a rotatable disc, 70 arms pivoted to said discs and supporting the spindles, a stationary cam slot disc, angularly disposed arms carried by the spindle arms, members carried by the angularly disposed arms and disposed in the cam slot 75 of the disc and cooperating with said cam slot whereby as the spindles approach the paper strip feeding position said spindles will have an advanced and then a retarded movement in relation to the other spindles. 80

6. A paper receptacle making machine comprising means for feeding strips of predetermined lengths, a twisting mechanism comprising a plurality of spindles having a planetary movement, gripping jaws carried by said spindles, a large stationary gear, pinions carried by sleeves rotatable with the spindles and meshing with the large gear, means for holding wrapped strips on the spindles, means for folding in the outer ends 90 of the strips on the spindles, means for moving said spindles axially and removing the gripping jaws from the receptacles, push rods extending through said spindles and axially movable in one direction therewith, 95 means for holding the push rods against rearward movement after an axial movement of the spindles, means carried by the push rods for engaging the inner ends of the receptacles, means for moving said spindles inwardly and means for allowing inward movement of the push rods after the inward movement of the spindles and before said spindles reach the paper strip feeding position. 100

7. A paper receptacle making machine comprising a strip feeding mechanism, a plurality of rotatable spindles having a planetary movement, strip gripping members carried by said spindles, spindle frames in which said spindles are rotatably mounted, a rotatable disc to which said frames are pivotally mounted, a stationary gear, pinions carried by said spindles and meshing with the stationary gear, a cam disc adjacent the spindle carrying disc, arms carried by the spindle frames, members carried by said arms and disposed in a concentric slot of the cam disc, a yieldable sector carried by the stationary gear adjacent the strip feeding mechanism, said cam disc having its cam slot adjacent the feeding mechanism inclined inwardly away from the feeding mechanism then outwardly towards the feeding mechanism and forming means 115 120 125 130

whereby the spindles are advanced in speed adjacent the feeding point and finally retarded for the gripping operation.

8. A paper receptacle making machine comprising a plurality of spindles having a planetary movement, means for feeding paper strips to said spindles at a feeding point, gripping jaws carried by said spindles, spring means for normally maintaining said jaws closed and means whereby said spindles are advanced in speed as they approach the feeding point and retarded in speed when at the feeding point.

9. A paper receptacle making machine comprising a plurality of spindles having a planetary movement, means for feeding paper strips to said spindles at a feeding point, gripping jaws carried by said spindles, means for normally maintaining said gripping jaws closed, means for opening and closing said jaws at the feeding point and means cooperating with the spindles whereby as the spindles approach the feeding point they are advanced and then retarded in relation to the other spindles whereby a delayed action is obtained for allowing for the gripping operation.

10. A paper receptacle making machine comprising a plurality of rotatable spindles having a planetary movement, means for feeding paper strips to said spindles at a feeding point, means for preventing unwrapping of the strips from the spindles, means movable into and out of the path of portions of the strips extending beyond the spindles for folding in one side of said strips and allowing passage of the other side of said strips, an arcuate plate having a constantly restricted cam slot in the path of the portions of the strips extending beyond the end of the spindles and forming means for twisting said portion thereby closing the outer ends of the strips and means for removing said receptacles from the spindles.

45 11. A paper receptacle making machine comprising a plurality of rotatable spindles having a planetary movement, means for feeding paper strips to said spindles at a feeding point, means for preventing unwrapping of the strips from the spindles, means movable into and out of the path of portions of the strips extending beyond the spindles for folding in one side of said strips and allowing passage of the other side of said strips, an arcuate plate having a constantly restricted cam slot in the path of the portions of the strips extending beyond the end of the spindles and forming means for twisting said portion thereby closing the outer ends of the strips, and a yieldable presser positioned whereby during the planetary movement of the spindles it will engage and apply pressure to the bottoms of the receptacles.

65 12. A paper receptacle making machine

comprising a plurality of rotatable spindles having a planetary movement, means for feeding paper strips to said spindles at a feeding point, means cooperating with said spindles for preventing unwrapping of the strips from the spindles, means movable into and out of the path of the portions of the strips extending beyond the spindles for folding in one side of said strips and allowing passage of the other side of said strips, an arcuate plate having a constantly restricted cam slot in the path of the portions of the strips extending beyond the end of the spindles and forming means for twisting said portions, said spindles being rotatably and axially movable, means for moving said spindles outwardly and inwardly and means for ejecting the receptacles from the spindles upon the inward movement thereof.

13. The combination with a paper receptacle making machine comprising a strip feeding mechanism, a plurality of spindles having a planetary movement, gripping members carried by said spindles and adapted to grip strip ends, of means whereby during the planetary movement of the spindles strip ends will be folded inwardly adjacent the outer ends of the spindles, the spindles moved outwardly independent of the gripping jaws, ejector rods moved outwardly simultaneously with the spindles, the spindles moved inwardly without inward movement of the ejector rods and the ejector rods moved inwardly to normal position before the spindles reach the feeding position.

14. A paper container making machine comprising a rotatable disc, a plurality of spindle frames pivotally connected to the disc, spindles rotatably and slidably mounted in said frame and having a planetary movement, gripping jaws carried by said spindles and adapted to grip strips at a feeding point, pinions carried by sleeves rotatable with said spindles and through which said spindles are slidably mounted, a large gear, said pinions meshing with said large gear, a yieldable gear segment carried by said large gear adjacent the feeding point, cam and cam slot means cooperating with the frame and forming means whereby they are advanced in arcuate movement as they approach the feeding position and retarded as they reach the feeding position, means for twisting the ends of the strip extending beyond the spindles during their planetary movement, means for removing said receptacles from said spindles, said means comprising rollers carried by the spindles, a guide ring with which said rollers engage, and an angularly disposed portion carried by said guide ring.

In testimony whereof I hereunto affix my signature.

IGNAZIO PIERMATTEI.
